UNITED STATES PATENT OFFICE

101,165

DESIGN FOR A GLIDER OR SIMILAR ARTICLE

Jacob C. Feldman, Boston, Mass., assignor to New
England Bedding Company, Medford, Mass., a
corporation of Massachusetts

Application June 30, 1936, Serial No. 63,584

Term of patent 14 years

To all whom it may concern:

Be it known that I, Jacob C. Feldman, a citizen
of the United States of America, residing at Bos-
ton, in the county of Suffolk and Commonwealth
of Massachusetts, have invented a new, original,
and ornamental Design for a Glider or Similar
Article, of which the following is a specification,
reference being had to the accompanying draw-
ing, forming a part thereof.

Fig. 1 is a perspective view of the glider show-
ing my new design; and

Figs. 2 and 3 are enlarged end and side eleva-

tional views, respectively, of the combination
end and arm rest element thereof.

The dominant feature of my design consists in
the combination end and arm rests of the glider,
shown in the full lines.

I claim:

The ornamental design for a glider or similar
article, substantially as shown and described.

Signed by me at Medford, in the county of
Middlesex, and Commonwealth of Massachusetts,
this 26th day of June, 1936.

JACOB C. FELDMAN.
